UNITED STATES PATENT OFFICE.

JULIUS M. ALTER, OF BROOKLYN, NEW YORK, ASSIGNOR TO WESTERN ENVELOPE CORPORATION, OF BROOKLYN, NEW YORK, A CORPORATION OF NEW YORK.

LOCKING-TONGUE ENVELOPE.

Application filed April 28, 1927. Serial No. 187,134.

This invention relates to that class of devices described and claimed in Letters Patent of the United States No. 1,461,016, issued on July 3rd, 1923, to the Western Envelope Corporation, on request of George R. Perry.

Whereas in the previously patented device which applicant is practising extensively, in the use of heavy materials for the making of the envelopes or containers, considerable difficulty arises in threading the locking tongue through the slots or under the keeper, one of the principal objects of the present improvement is to facilitate such actuation of the locking tongue as to make it easy at all times and irrespective of the thickness of the cardboard or paper, to effect the desired interlocking of the locking tongue.

With the foregoing and other objects in view the invention consists of the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a face view of the interlocking portions of an envelope made in accordance with this improvement, parts being broken away to show internal construction.

Fig. 2 is a fragmentary view similar to Fig. 1, but with the locking flap and tongue open:

Fig. 3 is a view similar to Fig. 2 but with the guide flap in open position.

Fig. 4 is a vertical transverse section on the line 4—4 of Fig. 1.

Referring now more specifically to the drawings, I show a container in the nature of an envelope and made of any suitable but preferably heavy stock of paper or cardboard and comprising a body 10 having a front panel 11 over which extends a sealing flap 12 having a sealing tongue 13. The front panel 11 is provided with a pair of substantially horizontal slots 14 and 15 spaced below the mouth 16 of the container and of any suitable design. As shown particularly, however, in Fig. 3, the slot 15 is composed preferably of a succession of curves forming a central downwardly extending lip 17 for which there was a corresponding feature in the previous patent

above specified. I do not require, however, that the slot 15 shall be cut of open form as in the previous case, a matter of economy of time and expense.

In the previous practice, the locking flap 12 and tongue 13 were folded into closed position as shown in Fig. 1, and the locking tongue 13 was projected downward and inward through the slot 14 and thence downward and outward through the slot 15. This procedure is practical and simple with a light or medium weight of stock, but when a heavy paper or cardboard is used, it is difficult for the end or point of the tongue 13 to be projected outward through the slot 15 under the old practice.

To overcome in a simple easy manner this difficulty, I now provide a guide member in the nature of a flap 18 carried by the edge or mouth portion of the front panel 11, either integral therewith or otherwise, but extending normally, before sealing, upward or outward in the direction of the open tongue 13, see Fig. 3. At any time, preliminary to the closing and sealing of the envelope, the guide flap 18 is folded downward and inward around the hinge line 19, and caused to project directly downward and outward through the slot 15 as in Fig. 2, where it lies substantially flat, or as far as the nature of the material will permit. As the end of the flap 18 passes thus outward through the slot 15, it passes beneath and lies directly against the locking tongue 17.

When the sealing flap 12 is brought down into closed position, bending around the hinge line 20, the point or end of the tongue 13 comes into position to pass freely and easily downward and inward through the slot 14, riding at this time directly along and over the then outer surface of the flap 18. The end, therefore, of the tongue 13 slides directly and easily and without obstruction along the guide flap 18 and is so caused to pass downward and outward through the slot 15, bringing the locking slot 21 formed therein into juxtaposition with the locking tongue 17. If now the projecting end of the tongue 13 be grasped between the thumb and finger of one hand, the slot 21 will be drawn downward or beyond the tongue 17, and the application of a slight pressure on said tongue 17 by the thumb of the other hand will bring the slot 21 and tongue 17 into interlocking engagement with each other.

The normal tension of the envelope parts and the friction between interlocking features will insure the permanent interlocking in the position shown in Figs. 1 and 4. To open the envelope, the operator has but to grasp again the end of the tongue 13 between the thumb and finger of one hand and draw the tongue downward, bringing the same out of interlocking engagement with the tongue 17. The locking flap and sealing tongue 13 may then be opened directly.

I claim:

1. In a locking tongue envelope, a body having a front panel, a sealing flap having a tongue co-operating with said panel, said panel having a pair of vertically spaced slits

and through which the tongue is adapted to be projected downward, and inward through the upper slit and outward through the lower slit, and means carried by said front panel and extending downward in the envelope and outward through the lower slit to compel the locking tongue to be guided therealong. 20

2. A device as set forth in claim 1 in which said means is a flap carried by the upper edge portion of the front panel and integral therewith, the same being folded downward and inward from the mouth of the envelope so as to pass downward and outward through the lower slit. 25

In testimony whereof I affix my signature.

JULIUS M. ALTER. 30
